INTERNAL COMBUSTION ENGINE VALVE

Heinrich Wälti, Winterthur, Switzerland, assignor to Sulzer Freres, Societe Anonyme, Winterthur, Switzerland

Application November 13, 1936, Serial No. 110,643
In Switzerland December 18, 1935

2 Claims. (Cl. 251—144)

This invention relates to spring actuated fuel valves for internal combustion engines and has for its object the provision of an improved valve of this character.

5 It has been proposed to load the valve needles of fuel injection valves for internal combustion engines, which are opened by the pressure of the fuel, by spiral springs. Such spiral springs require a suitable housing and as the 10 springs must be strong enough to close the fuel valve against high pressures they must be of substantial length, thus necessitating spring housings of such length that they project outwardly far beyond the engine cylinder. That 15 is particularly objectionable in internal combustion engines of the rocker counter-piston type in which it is usual to position the fuel injection valves between the cylinders of the engine. In order to reduce the length of the 20 spring housing it has been proposed to replace the spiral springs by beam or laminated springs, both ends of which are laterally movable between guides and are adjustable, and the central part, which loads the valve needles, cooperating with 25 a displaceable stop. As such springs are nowhere firmly clamped the resulting structure necessary to carry the adjacent parts is bulky and projects over the cylinder jacket, thereby making it difficult to closely juxtapose several 30 cylinders and to obtain an exact setting or adjustment of the springs before installation.

In order to avoid the objections to beam and laminated springs as above referred to, twistable bar springs having their axes extending laterally 35 from the axes of the needle valves were tried but were not satisfactory as one or more powerful transmission members between the bar spring and the needle valve had to be provided. Necessarily, the result was a separate mounting of the 40 bar spring and needle valve which made possible an adjustment of the spring only after the assembly of the internal combustion engine had been completed. Furthermore, adjustment was difficult where the valves had to be placed in the 45 space between adjacent cylinders.

The present invention avoids the above disadvantages by the use of an integral spring rod for loading the valve needles, with the end of the spring rod furthest from the injection 50 valve being firmly fixed in an extension of the valve casing or housing, while the free end of the spring rod, which loads the valve needle, is movable outwardly in the direction in which the needle valve extends, whereby the needle valve 55 is placed under load. Such arrangement results

in a very compact construction and a smoother and easier action of the spring tension than can be attained with twistable bar springs, or with beams held on both sides, or with laminated springs of the type referred to above. 5

In order to eliminate from the start the free spring stroke up to the desired initial tension of the spring, which no longer is required after the assembly is completed, and to reduce the length of the spring casing, it is proposed by 10 the present invention to position the spring rod so that it extends laterally of the needle valve in a lateral extension of the casing or housing of the injection valve. Thus, there is obtained an extremely small construction length for the 15 part of the valve housing which projects over the cylinder jacket. Moreover, as all the parts are placed in a common housing, a previous exact adjustment of the spring to the needle valve can be made so that adjustments after installation 20 of the injection valve in the internal combustion engine will be necessary only in rare instances.

The firm securing of the end of the spring 25 rod furthest from the injection valve to the extension of the valve casing or housing preferably is effected by providing that end with a conical portion which diverges from the valve needle and having it seat on a similarly formed portion of the extension of the valve casing or housing. 30

The invention will be better understood from a consideration of the following description taken in conjunction with the accompanying drawings, in which:

Figure 1 is a partial section through a fuel 35 valve in accordance with the invention.

Figure 2 is an illustration of an adaptation of the valve of the invention to internal combustion engines, and

Figure 3 is a section along line 3—3 of Figure 2. 40

In the drawing, with particular reference to Figure 1, the fuel-valve 1 is shown in operative position mounted in engagement with the jacket 2 and cylinder wall 3 of an internal combustion 45 engine. The housing 4 has an extension 5 fitting into a bore 6 in the jacket 2 and a nozzle 7 is attached to the extension 5 by means of the coupling 8.

The housing 4 has an angularly disposed extension 9, in which an opening 10, preferably a cylindrical bore, is formed throughout the greater part of its length. At the free end of the extension 9 the bore is conical. The extension 5 has a central opening or bore 11 in communica- 50 55

tion with the bore 10, the two being crosswise to each other, meeting preferably at right angles.

The needle portion 18 of the valve is not completely shown, parts thereof being within the nozzle 7. A conduit 12 is formed in the extension 5 and leads from a suitable source of oil (not shown) to the nozzle where it acts in the conventional manner upon the needle of the valve. A push-rod 13 disposed in the axial direction of the needle 18 and in engagement therewith, is mounted in the bore 11, the upper end of which extends into the bore 10. (The axial direction of the valve, it will be noted, in the adaptation of the invention illustrated, is substantially radial to the cylinder bore.)

A bar spring 15, having an end portion of conical form is securely fitted into the conical end-portion of the bore 10, is held fast by the cap screw 16 and is prevented from turning by the pin 17. The remaining portion of the spring 15 tapers in the direction of its opposite end which has a flattened portion in pressed engagement with the rod 13. The conical part of the extension 9 and the end carrying the cap screw are so formed that the geometrical axis 19 thereof meets the push-rod a few millimeters below its upper end. As thus constructed and arranged the spring is under tension and presses against the rod 13.

An illustration of an adaptation of the valve of the invention is shown in Figs. 2 and 3 in which the internal combustion engine (a rocker counter-piston type) has cylinders 3, jackets 2, pistons 20, piston rods 21, rocker levers 22, connecting rods 23 and a crankshaft 24. In engines of this type, into which the fuel must be injected into the combustion chamber through the cylinder, it is desirable to inject the fuel into the combustion chamber from each of two diametrically opposite points. It will be noted that, in engines of this type, the fuel valves must not be located on the crank-side of the cylinders because they would be inaccessible. With the fuel valves according to the present invention this difficulty is eliminated in a simple manner by arranging the valves in the plane of the axes of the cylinders. Because the fuel valves of the invention may be made very short in the direction of the valve

axis, it is possible to install and remove them easily, without the necessity of increasing the distance between the cylinders.

In operation, the needle valve is opened in the conventional manner by the pressure of oil fed into the conduit 12 during the compression stroke of the fuel pump (not shown). When this pressure is released, the needle valve is instantly closed by the pressure exerted upon the push-rod 13 by the spring 15.

I claim:

1. A fuel injection valve assembly for internal combustion engines in which the valve member is adapted to close against a high fuel pressure, which comprises an angular housing having a pair of intersecting bores, one located in each angular portion of the housing, and a conical seat in axial alignment with one of said bores, an injection valve needle mounted in one of said bores, a spring rod mounted in the other bore, said spring rod having the end furthest from the valve needle provided with a conical portion, and means for holding the conical portion of said spring rod against the conical seat of the valve housing to thereby firmly secure said spring rod to the valve housing, and the free end of said spring rod loading the valve needle and being movable outwardly in the direction in which the valve needle extends.

2. A fuel injection valve assembly for internal combustion engines in which the valve member is adapted to close against a high fuel pressure, which comprises an angular valve housing having a pair of intersecting bores, one located in each angular portion of the housing and a conical seat in axial alignment with one of said bores, an injection valve needle mounted in one of said bores, a tapered unitary spring rod mounted in the other of said bores, a portion of said spring rod furthest from the valve needle bearing against the conical seat in said valve housing, and means for holding said end of the spring rod against said conical seat to firmly secure said end of the spring rod to the valve housing, the free end of said spring rod loading the valve needle and being movable outwardly in the direction in which the valve needle extends.
